[57] CLAIM

The ornamental design for a tongue cleaner, as shown and described.

DESCRIPTION

FIG. 1 is a diagrammatic perspective view of the tongue cleaner in full lines with a person shown in broken lines representing environmental association matter being for illustrative purposes only and forming no part of the claimed invention.

FIG. 2 is a front elevational view thereof, the rear elevational view being a mirror image of the front view.

FIG. 3 is a right side elevational view thereof, the left side elevational view being a mirror image of the right side view.

FIG. 4 is a top plan view of the tongue cleaner; and,

FIG. 5 is a bottom plan view thereof.
